DESIGN FOR A CASING FOR A KEYBOARD FOR TICKET ISSUING MACHINES

Hilding L. Pierson, Brooklyn, N. Y., assignor to
Silent American Ticket Machine Co., Long
Island City, N. Y.

Application October 9, 1933, Serial No. 49,424

Term of patent 7 years

To all whom it may concern:

Be it known that I, HILDING L. PIERSON, a subject of the King of Sweden, residing at Brooklyn, county of Kings, and State of New York, have invented a new, original, and ornamental Design for a Casing for a Keyboard for Ticket Issuing Machines, of which the following is a specification, reference being had to the accompanying drawing, forming part thereof.

Fig. 1 is a perspective view of the article, showing my new design; and

Fig. 2 is a broken plan view thereof.

The parts of the casing shown in dotted lines in both figures are not a material part of the design.

I claim:

The ornamental design for a casing for a keyboard for ticket issuing machines, substantially as shown and described.

HILDING L. PIERSON.
